CLAIM

The ornamental design for a valve flapper, as shown and described.

DESCRIPTION

FIG. 1 is a top perspective view of a valve flapper, functionally deployed in place on a valve housing (illustrated in phantom);

FIG. 2 is a front view of the valve flapper of FIG. 1;

FIG. 3 is a rear view thereof;

FIG. 4 is a right-side view thereof;

FIG. 5 is a left side view thereof;

FIG. 6 is a top plan view thereof;

FIG. 7 is a bottom plan view thereof;

FIG. 8 is a top front perspective view thereof; and,

FIG. 9 is a bottom rear perspective view thereof.

The broken lines in FIG. 1 which illustrate a valve housing and valve hinge depict environmental subject matter that forms no part of the claimed design.
